UNITED STATES PATENT OFFICE.

WALTER P. MURPHY, OF NEW YORK, N. Y.

CORRUGATED-SHEET-METAL CAR END.

Application filed July 17, 1920. Serial No. 397,110.

To all whom it may concern:

Be it known that I, WALTER P. MURPHY, a citizen of the United States, residing at New York, in the county of New York and State of New York, have invented a new and useful Improvement in Corrugated-Sheet-Metal Car Ends, of which the following is a specification.

This invention relates to improvements in end structure for railway cars and more particularly to corrugated sheet metal ends for freight cars.

The end of a freight car is subject to very severe shocks and stresses due, among other things, to the tendency of the cargo to shift when the train stops and starts and to the tendency of the superstructure of the car to weave. The ends of this type of car have been constructed of one or more sheets or panels of metal, usually steel, which are formed with corrugations for the purpose of rigidifying and strengthening the structure against impacts from without and cargo thrusts on the inside and against racking strains due to weaving.

It is the object of this invention to provide a corrugated sheet metal car end, the corrugations of which have such contour as to give maximum strength and which affords a maximum resistance to the severe shocks and stresses to which the car end structure is necessarily subjected.

While the accompanying drawings illustrate this invention in connection with a certain type of car and form of end, it is not restricted thereto as the essence of the invention lies in the form or shape of the corrugation and may be used on any form of sheet metal end on any type of car.

In the drawing, Figure 1, is a view in end elevation of a box car to which this invention has been applied, with parts broken away.

Figure 2, is an enlarged detail view in section taken on the line 2—2 of Figure 1.

As shown, the car end is composed of a number of sheets of metal, 1 secured to each other and to the side walls, end sill and roof framing in the usual manner. Each sheet is formed with a plurality of parallel corrugations 2 tapering into the body of the sheet at each end.

The particular shape of the corrugation formed in accordance with this invention is clearly illustrated in the enlarged detail view of Figure 2.

The ridges of the corrugations alternate above and below the neutral axis of the plate with all of the apices of the ridges on the same side of the neutral axis lying in a plane parallel to said axis and a distance from the axis equal to the distance between the same and the plane of the apices on the opposite side. The centers of the alternating ridges are equal distances apart when projected upon the neutral axis. The apex of each ridge is joined by a web 3 to the apex of the adjacent ridge on the opposite side of the neutral axis. The webs forming the sides of a ridge are continued through the apex in the form of a curved arch 4 the crown of which is on the arc of a circle merging on each side into the walls on the arc of a circle of considerably smaller radius and from there the walls are straight from the crown of one ridge to the crown of the adjacent alternating ridge.

By this construction the ridges are trussed to each other by straight webs of maximum extent which are formed at but a slight angle to the perpendicular from the neutral axis which is a great advantage as the nearer the web approaches the perpendicular the greater the strength of the corrugated plate to resist external forces. The webs forming the sides of a ridge being connected by an arch forms an apex of greater strength than a flat top in resisting external forces and also adds to the strength of the corrugation by increasing the amount of metal at the greatest distance from the neutral axis.

While in the form of end illustrated, the corrugations are shown as pressed from one side of the normal plane of the plate, the invention is not restricted to this form alone as corrugations of the specific contour described herein may be pressed to project from opposite sides of the normal plane of the plate as well. Furthermore, the manner of forming the corrugations is not limited to pressing and the plate may be corrugated in any desired manner.

What I claim is:

1. A sheet metal plate for car ends having a plurality of parallel corrugations therein with the ridges of the corrugations formed on the arc of a circle merging on arcs of lesser radii into webs connecting the adjacent ridges.

2. A sheet metal plate for car ends having a plurality of parallel corrugations formed

therein, said corrugations formed on alternate sides of the neutral axis of the plate with the ridges of the corrugations formed on the arcs of circles merging on arcs of lesser radii into webs connecting the adjacent ridges.

3. A sheet metal plate for car ends having a plurality of parallel corrugations formed therein, said corrugations equally spaced apart and alternating on opposite sides of the neutral axis of the plate with the ridges of the corrugations formed on the arc of a circle merging on arcs of lesser radii into webs connecting the adjacent ridges.

4. A sheet metal plate for car ends having a plurality of parallel corrugations formed therein trussed to each other by flat webs with the crown of the ridge formed on the arc of a circle merging into the webs on arcs of lesser radii than that of the crown.

5. A sheet metal plate for car ends having a plurality of parallel corrugations formed therein, the ridges of said corrugations extending alternately on opposite sides of the neutral axis of the plate and trussed to each other by flat webs with the crown of the ridge formed on the arc of a circle merging into the webs on arcs of lesser radii than that of the crown.

6. A sheet metal plate for car ends having a plurality of equally spaced apart par-

allel corrugations formed therein, the ridges of said corrugations extending alternately on opposite sides of the neutral axis of the plate and trussed to each other by flat webs with the crown of the ridge formed on the arc of a circle merging into the webs on arcs of lesser radii than that of the crown.

7. A sheet metal car wall panel formed with strengthening ribs, the sides of which are flat and the ridges arched and joined to the flat side portions on curves of lesser radii than the radii of the ridges.

8. A sheet metal car wall panel formed with strengthening ribs, the sides of which are flat and sloping and the ridges arched and joined to the flat sloping side portions on curves of lesser radii than the radii of the ridges.

9. A sheet metal car wall panel formed with strengthening ribs, the ends of the ribs tapering and merging into the body of the panel, the sides of the ribs flat, and the ridges arched and joined to the side portions on curves of lesser radii than the radii of the ridges.

10. A sheet metal car wall formed with pressed corrugations, the sides of the corrugations being flat and the ridges arched and joined to the side portions on curves of lesser radii than the radii of the ridges.

WALTER P. MURPHY.
